UNITED STATES PATENT OFFICE

1,989,234

FLASHING

Louis Isgur, Boston, Mass., assignor to E. Van Nordeen Company, Boston, Mass., a corporation of Massachusetts

Application March 11, 1932, Serial No. 598,205

6 Claims. (Cl. 72—127)

The invention relates to an improvement in flashing of that type in which the flashing is set into the mortar joint between courses of masonry in a wall to extend through the wall and provide a shield for preventing moisture passing downward through the wall to a point below the flashing, and for diverting to the face or faces of the wall all moisture that passes downward through it to the point of the flashing.

10. Among the objects of the invention is to provide a relatively thin flashing of sheet metal capable of easy setting and firm bonding to the mortar within which it is set; to provide a flashing from which moisture or water will be diverted to the face or faces of the wall within which the flashing is set and will not pass through the wall from a point above to a point below the flashing; to provide a flashing which may be laid in successive aligned strips joined by interlocking the ends of the strips, and especially to provide means whereby water will not pass between the strips at the points of their interlocking and will be diverted at these points.

The invention can best be seen and understood by reference to the drawing in which an embodiment thereof is shown, and in which—

Figure 1 is a plan of the flashing.

Fig. 2 is a cross section showing the manner of its application.

30. Fig. 3 is a section on the line 3—3 of Fig. 2.

Fig. 4 is a section on the line 4—4 of Fig. 2.

Fig. 5 is an enlarged cross section of a detail of construction, and

Fig. 6 shows in perspective a further detail of construction.

Referring to the drawing:—

1 represents a strip of the flashing made of sheet metal. When applied to a wall the flashing is laid to extend lengthwise the wall within the mortar joint between courses of masonry 3 and 4. The length of each strip is such as will permit it to be conveniently handled. The width of the strip will vary depending upon the width of the wall to which it is applied. In practice the strip is oftentimes wider than the width of the wall, the side edge portions of the strip where they occur projecting beyond the face or faces of the wall to form flanges 5 which are turned up or down.

50. The strip is provided with a relatively broad raised tenon 7. This tenon is formed by bending the metal of the strip. The tenon runs lengthwise the strip along its centre or at such points so far removed from the sides of the strip 55 that it will lie fully contained within any joint

within which the strip is embedded. The tenon is provided with sides 8 preferably inwardly inclined. At spaced intervals throughout its length the strip is provided with cross gutters 9. These gutters are formed by flattening the metal of the tenon at the points of the gutters to lie substantially flush with the top surface of the strip. This flattening of the tenon leaves the tenon or sections thereof lying between the gutters with ends 10 running crosswise the strip.

When the strip is embedded in the mortar joint formed in the wall the tenon 7 will interlock with, and thereby become bonded to the mortar in the joint lying above the strip. The strip will be held also against lateral and endwise displacement by the bearing of the sides 8 and ends 10 of the tenon, or sections thereof, against the mortar. The mortar lying within the joint on the under side of the flashing will enter the hollow of the tenon to interlock therewith and thereby become bonded to the strip while the inner faces of the sides and ends of the tenon, by their bearing against the mortar, will assist in preventing lateral and endwise displacement of the strip. Thus the strip is held against displacement in all directions. All water or moisture seeping through the wall to the point of the flashing will be directed outside the wall by way of the gutters.

The ends of the strips are so formed that when the strips are aligned the ends will interlock with one another, and in such manner as will not permit of the passage of water between the strips at the interlocking points. To this end each strip is provided with gutters 9' 9'' adjacent its respective ends. At one end where occurs the gutter 9' the strip is turned upwardly from beyond the gutter by a portion 12 to a point about flush with the top surface of the tenon 7 on the strip. Thence the strip is turned back in a horizontal direction to form a tongue 13 which constitutes, as will later be explained, one of the interlocking members. At its opposite end where occurs the gutter 9'' the strip is extended upwardly from beyond the gutter by a portion 14 which rises to a point slightly above the top surface of the tenon 7, and this preferably in an amount substantially equal to the thickness of the metal. Thence the strip is extended forward in a horizontal direction and looped back upon itself to form a socket-forming member 15 within which the tongue 13 on the end of an adjacent strip is contained for forming the interlocking connection between adjacent strips when the strips are brought into proper alignment with one another.

With the individual strips of the flashing thus connected it will be seen that there is provided a series of raised tenons 7 removed from the sides of the flashing with extension longitudinally thereof. Each of the tenons has sides 8 and ends 10, the metal of the strip being bent to form gutters crossing the flashing at intervals with extension through the tenons by which water may pass from one side of the flashing to the other, the gutters imparting, also, the ends 10 to the raised tenons. The flashing joints between the strips lie well above the bodies of the strips. Gutters are provided on the respective strips at points adjacent the flashing joints between them, the joints lying well above these gutters and immediately above one of the gutters. Consequentially, in order for moisture or water to pass through the flashing at the points of the joints between its strips the water must pass upwardly by the free end of the socket-forming member 15, thence through the socket and upwardly by the free end of the tongue 13. Such passage of water is practically impossible inasmuch as it cannot flow upwardly. Instead any water which might accumulate at the points of the flashing joints will pass off into one or the other of the adjacent gutters, while any water which might accumulate on the under side of the socket-forming members 15 will pass off the free end of this member into the gutter below.

Not only does the raising of the flashing joints above the bodies of the strips possess the advantage of preventing passage of water through the strips at the points of the joints, but a further material advantage is obtained. As previously described, the flashing is often made wider than the width of the wall with flanges 5 bent upwardly or downwardly to bear against the face or faces of the wall as shown in Figs. 3 and 6. By raising the flashing joints above the bodies of the strips, as they are in fact raised by the strip portions 12 and 14 respectively, the bodies of the strips may then be initially formed with flanges and the interlocking joint continued around the bend for making the flanges, after which the individual units may be applied to the wall and locked together. The making of a bend in the strip for forming the flange tends to flatten the socket which receives the tongue, preventing entrance of the tongue, and if the joint is not raised this would be the effect and the flange 5 could only be formed after the strips have been applied to the wall and locked together. By raising the joint any distortions arising from the bending for forming the flange will concentrate on the strip portions 12 and 14 which carry the joint and these portions will become more or less flattened but the joint itself will be left intact.

Having thus fully described my invention, I claim and desire to secure by Letters Patent of the United States:—

1. A flashing comprising connected strips of sheet metal bent to form a series of raised tenons removed from the sides of the flashing with extension longitudinally thereof each of said tenons having sides and ends, the metal of the strips being also bent to form gutters crossing the flash-

ing at intervals with extension through the tenons whereby said ends will be imparted to the tenons, and means connecting said strips.

2. A flashing comprising end connected strips of sheet metal bent to form a series of raised tenons removed from the sides of the flashing with extension longitudinally thereof, the metal of the strips being also bent to form gutters crossing the flashing with extension through the tenons, said gutters being located on separate strips at 10 points adjacent the connected ends thereof, and interlocking members forming the end connection between the strips and located above said gutters, the metal of the respective strips extending from said gutters to form said interlocking members. 15

3. A flashing comprising end connected strips of sheet metal bent to form a series of raised tenons removed from the sides of the flashing with extension longitudinally thereof, the metal of the strips being also bent to form gutters crossing the flashing with extension through the tenons, said gutters being located on separate strips at points adjacent the connected ends thereof, and interlocking members comprising a tongue and a socket-forming member in which said tongue is contained forming the end connection between said strips and located above said gutters, the metal of the respective strips extending from said gutters to form said tongue and socket-forming member respectively. 20

4. A flashing comprising a strip of sheet metal bent to form a raised tenon removed from the sides of the flashing with extension lengthwise thereof, the metal of the strip being also bent to form gutters crossing the strip with extension 35 through the tenon adjacent the ends of the strip, and members borne by the strip at the respective ends thereof adapted to form interlocking connection with members on the ends of adjacent strips, said members borne by the strip being 40 formed by extending the metal of the strip from the respective gutters.

5. A flashing comprising a strip of sheet metal bent to form a raised tenon removed from the sides of the flashing with extension lengthwise thereof, the metal of the strip being also bent to form gutters crossing the strip with extension 45 through the tenon adjacent the ends of the strip, a tongue borne by the strip at one end, and a socket-forming member borne by the strip at its 50 opposite ends, said tongue and socket-forming member being formed respectively by extending the metal of the strip from the respective gutters to which the tongue and socket-forming member lie adjacent.

6. A flashing comprising end connected strips of sheet metal with turned flange extending from said strips at the side thereof, interlocking members comprising a tongue and a socket forming member in which the tongue fits to form a connecting joint between said strips and which joint is continued through said flange, and strip portions raising the interlocking members forming said joint above the bodies of the strips whereby said joint will be left intact and said tongue may enter to fit within said socket after the bending of the strips at the flashing to form said flange. 60

LOUIS ISGUR.

CERTIFICATE OF CORRECTION.

Patent No. 1,989,234.

January 29, 1935.

LOUIS ISGUR.

It is hereby certified that error appears in the printed specification of the above numbered patent requiring correction as follows: Page 2, second column, line 51, claim 5, for "ends" read end; and line 67, claim 6, for "at" read of; and that the said Letters Patent should be read with these corrections therein that the same may conform to the record of the case in the Patent Office.

Signed and sealed this 5th day of March, A. D. 1935.
